UNITED STATES PATENT OFFICE

157,310

THERAPEUTIC EXERCISING SEAT

William L. Wettlaufer, Buffalo, N. Y.

Application December 2, 1948, Serial No. 149,923

Term of patent 14 years

(Cl. D15—1)

To all whom it may concern:

Be it known that I, William L. Wettlaufer, a citizen of Canada, residing at Buffalo, in the county of Erie and the State of New York, have invented a new, original, and ornamental Design for a Therapeutic Exercising Seat, of which the following is a specification, reference being had to the accompanying drawing, forming a part thereof.

In the drawing,

Fig. 1 is a perspective view of said therapeutic exercising seat, taken from the front end, and showing my new design.

Fig. 2 is also a perspective of said seat, as viewed from the front and right hand side.

Fig. 3 is a perspective as viewed from the top.

Fig. 4 is a perspective of the seat as viewed from the rear and side opposite to that in the foreground in Fig. 2.

I claim:

The ornamental design for a therapeutic exercising seat, as shown.

WILLIAM L. WETTLAUFER.
